UNITED STATES PATENT OFFICE.

WILLIAM BRIGHT, OF KIMBERLY, UTAH.

GLASS-TUBE WATER-GAGE FOR STEAM-BOILERS.

SPECIFICATION forming part of Letters Patent No. 718,046, dated January 6, 1903.

Application filed May 22, 1902. Serial No. 108,590. (No model.)

To all whom it may concern:

Be it known that I, WILLIAM BRIGHT, a citizen of the United States, residing at Kimberly, county of Piute, and State of Utah, have invented certain new and useful Improvements in Glass-Tube Water-Gages for Steam-Boilers, of which the following is a specification.

My invention relates to glass-tube water-gages for steam-boilers.

10 The object of the present invention is the provision of an improved and novel automatically-acting valve for use in connection with glass-tube water-gages which will normally remain open and not interfere with the 15 rise and fall of the water in the glass tube of the gage, but which will automatically close by the pressure of the steam upon the breaking of the glass tube, thereby shutting off the steam-pressure and preventing scalding or 20 injury to any person near the water-gage and also permitting the steam to be shut off at leisure in the regular way by closing the ordinary globe-valve used on water-gages.

The invention consists of certain improved 25 features and novel combinations of parts set forth in detail hereinafter and recited in the appended claim.

In the accompanying drawings, Figure 1 is 30 a view of a glass-tube water-gage to which my invention is applicable, and Fig. 2 an enlarged section illustrating the invention.

The numeral 1 designates the glass tube of the water-gage, while 2 and 3 are fittings at the ends of the tube 1, which are provided 35 with globe-valves 4, by which the steam or water can be shut off from the glass tube 1 in a well-known manner.

In Fig. 2 I have shown my invention as used in connection with the lower fitting 3; 40 but it can be used as well with the upper fitting 2.

The fitting 3 consists of a shell 5, interiorly recessed at 6, while the lower portion of the fitting is made into the larger shell 7, into 45 which screws the plug or head 8, provided with the petcock 9.

The numeral 10 designates a three-leaf check-valve, whose head 11 is provided with an annular groove 12 on its upper face, and 50 the head 11 is adapted to close on the seat 13. The head 11 is located in the shell 7 and pro-

vided with a stem 14, having a notched lower end 15, adapted to straddle the passage through the petcock-casing 9 and to rest against the said casing, and it is of such 55 length that it will allow the valve-head 11 to remain unseated in a suitable manner under ordinary circumstances. A coil-spring 16, which surrounds the leaves of the valve and is located in the counterbore or recess 6 and 60 has its upper end seated against a shoulder 17 and its lower end seated in the groove 12, keeps the valve normally pressed down, with its stem bearing against the plug 8. The valve is thus normally kept open; but should 65 the glass tube 1 break the steam will immediately rush from the boiler through the fitting and act against the face of the valve-head 11, causing it to close immediately, and thus confining the steam in the fitting. The 70 steam is thus effectually checked by the check-valve and again later cut off by closing the globe-valve 4 when it is convenient to do so.

Having thus described my invention, what 75 I claim as new, and desire to secure by Letters Patent, is—

In a device of the class described, the combination with a fitting for the glass tube, said fitting comprising a shell of different internal diameters and a seat whereby the portions of the shell join, and the smaller portion of the shell being internally recessed or counterbored, of a plug connected to the larger portion of the shell, a petcock connected to 80 the plug, and a check-valve comprising leaves, a head having a groove and which is adapted to fit the seat, and a stem on the head which is provided with a bifurcated lower end, and a coil-spring located in the counterbore and 85 surrounding the leaves of the valve and seated in the groove in the valve-head, said spring keeping the valve normally unseated and the stem being adapted to bear on the plug and limit the opening of the valve. 90

95 In testimony whereof I hereunto affix my signature in presence of two witnesses.

WILLIAM BRIGHT.
